METHOD OF MAKING RADIATORS

Original Filed Aug. 25, 1922

INVENTOR:
Edmund B. Lennig.

ATTORNEYS

UNITED STATES PATENT OFFICE.

EDMUND B. LENNIG, OF SAN FRANCISCO, CALIFORNIA, ASSIGNOR TO ELECTRIC RADIATOR & ENGINEERING CO., INC., OF SAN FRANCISCO, CALIFORNIA, A CORPORATION OF CALIFORNIA.

METHOD OF MAKING RADIATORS.

Original application filed August 25, 1922, Serial No. 584,176. Divided and this application filed September 7, 1923. Serial No. 661,435.

To all whom it may concern:

Be it known that I, EDMUND B. LENNIG, a citizen of the United States, residing in the city and county of San Francisco, State 5 of California, have invented a new and useful Method of Making Radiators, of which the following is a specification.

The present invention relates to electrical- 10 ly heated radiators, and more especially to a novel method of making an electric heater for radiators and the like, and is disclosed by and constitutes a division of my prior application for a patent for electric radiator, filed August 25, 1922, under Serial No. 584- 15 176.

Among the objects of the invention are to provide a novel method of making radiators and more especially electric radiators whereby a maximum amount of heat with a mini- 20 mum amount or consumption of electric current is obtained, while at the same time providing means to automatically store heat or to provide latent heat.

A further object of my invention is to pro- 25 vide a novel method of making electrical radiators whereby a portable radiator is produced having electrical resistance or heating coils or units adapted to be connected by means of a plug connection hav- 30 ing a lead, or otherwise, with a socket or other connection to the wiring of a house or building for heating purposes and which obviates the necessity of employing a furnace or central heating plant, pipes, flues 35 or chimneys and the wastes due to radia- tion while the heating medium is in transit to and from the place of use or various rooms to be heated.

Another object of the invention is to de- 40 vice an electric radiator in which a storage of heat or latent heat is obtained by means of clay products such as marbles or the like.

Other novel features of construction and advantage will hereinafter more clearly ap- 45 pear in the detailed description of my in- vention.

For the purpose of illustrating my in- 50 vention, I have shown in the accompanying drawings certain forms thereof which are at present preferred by me, since the same will give in practice satisfactory and re- liable results, although it is to be under-

stood that the various instrumentalities of which my invention consists may be vari- 55 ously arranged and organized and that my invention is not limited to the precise ar- rangement and organization of these instru- mentalities as herein shown and described.

Figure 1 represents a vertical section of an electric radiator embodying my inven- 60 tion.

Figure 2 represents on enlarged scale a longitudinal sectional view, partly in ele- vation, of one of the heating elements.

Figure 3 represents a section on line 3— 65 3 Figure 2.

Figure 4 represents an end view of Fig- ure 1.

Similar numerals of reference indicate 70 corresponding parts.

Referring to the drawings:—

1 designates my novel construction of electric radiator, the same comprising the radiator sections 2, which are of substan- 75 tially the same construction and are held in assembled position by the upper threaded nipples 3, and the lower enlarged threaded nipples 4, whereby an enlarged transverse lower chamber 5 is formed for the recep- 80 tion of the unit comprising the heating coil holders 6 and their adjuncts.

Each of said holders comprises an outer tubular casing or brass tubing 7, closed at one end, as indicated at 8, and open at the other end. Within each tubing or casing 7 is inserted the hollow or tubular insulating casing 9, within which is contained the core or insulation 10, about which latter is wound the heating coil 11, the latter being contained between the insulating elements 90 9 and 10 and its outer terminals 12 and 13 projecting as shown in Fig. 2, so as to enable the desired electrical connections to be made.

As the construction and manner of assembling each of the heating coils with 95 respect to their insulating core and casing is the same, a description of one will suffice for all. The core 10 is provided with the head 9*, see Figure 2, and, as will be seen from the left of Figure 1, the head 9* projects a short distance beyond the tubing 7 and passes through a hole in an insulating disc or plate 14, in proximity to which is an outer insulating plate or disc 15 upon

which the various electrical connections and binding posts are supported so as to be readily accessible, as will be understood from Figure 1.

- 5 The left hand ends of the plurality of outer casings or tubings 7, which constitute the enclosures for the heating elements are secured or brazed in the outer wall 16 of the head 17, which is mounted in the outer 10 lower portion of the left hand radiator section 17*, as will be understood from Figure 1, the inner or right hand portion of said head being of reduced diameter and threaded, as indicated at 18, so as to engage the 15 lower contiguous portions of the outer left-hand radiator sections so as to couple them together and form a seal to prevent liquid entering the left-hand radiator section 17*, seen in Figure 1, a tight joint being effected 20 by means of the gasket 16*.

I have shown the tubes 7 containing the heating coils and their adjuncts as being preferably six in number and by assembling them in the detachable head 17, the tubes 25 and head and the heating coils within said tubes can be withdrawn and replaced as a unit, as will be understood from Figure 1, so that any tube and its heating coil is readily and instantly accessible for the purposes 30 of inspection, replacement or repair, as will be understood from Figure 1. The threaded portion 18 serves to couple the two right-hand end sections together and the shoulder and gasket 16* seen at the lower left-hand 35 portion of Figure 1 form an effective seal to prevent leakage into the left-hand radiator section 17*, which contains the thermostat and the wires leading thereto, to be referred to. The current is conducted into the radiator through the wires 19 and 20, which are suitably insulated, said wires passing through the hole 21 of the outer cap 22 secured to the outer casing 23, so that upon the removal of said cap immediate access is 40 had to all the wiring connections. 45

A suitable switch may be provided in the wires 19 and 20 from which one wire leads to the member 24 of a thermostat 25 while the other wire leads to a binding post 50 of the plate 15 from which a wire corresponding to the wire 12 leads to one of the heating coils 11.

The thermostatic member 25 is located at the upper left hand portion of the radiator 55 section 17* as seen in Figure 1, and as the same is preferably constructed in conformity to the thermostat seen in my prior Patent No. 1,391,239, granted September 20, 1921, the construction and operation of the same 60 need not be described in great detail, as the manner of making the wiring connections will be readily apparent from my patent aforesaid, wherein I have shown the collocation of the six heating coils and the wiring 65 connections therefrom to the outer in-

sulating disc 15 and to the bottom member 24 of the thermostat 25.

26 designates a head having the threaded extension 27 which forms a coupling connection for the upper left hand portions of the two left hand radiator sections, as will be understood from Figure 1, said head having the air tube or tubing 28 secured therein, the opposite end of said tubing being closed as indicated at 29 said tubing serving as 70 an air tube and said upper head 26, together with the lower head 17, serving as a closure to keep liquid out of the left hand radiator section 17*, which is thus isolated from the other radiator sections, as will be understood 75 from Figure 1. The air tube 28 is of less diameter than the nipples 3 as will be understood from Figure 1, so that the circulation of the liquid through the upper portion of the radiator is not impeded.

85 The outer or left hand end of the air tube 26 is constructed as seen in Figure 1, so that by the application of a suitable wrench the tube can be screwed into place.

80 The radiator sections, with the exception 90 of the left hand section 17* seen in Figure 1, are filled with a suitable heating medium, such as oil, as indicated at 30, and each 95 radiator section is also filled with clay spheres or marbles, as indicated at 31, contained within the radiator columns 32.

100 In equipping my novel radiator for the market, the parts are first assembled substantially as seen in Figure 1, with the oil or liquid heating element 30 supplied thereto and clay marbles 31 constituting refractory bodies. Before sealing up the openings, the electrical energy is turned into the coils and the liquid allowed to heat to a greater temperature with all of the coils in 105 active use than under actual working conditions. As the heat increases in the radiator, the liquid expands and the excess of the liquid and air is allowed to drain or escape from the radiator. When the excess 110 temperature, say 250 degrees Fahr. has been reached in testing the radiator, it is then sealed and allowed to cool. The liquid, in 115 cooling, shrinks to its normal density, thus creating an empty space or vacuum in the 120 radiator.

125 Thus, when the radiator is not in operation, it is under vacuum and when the radiator is in actual working use, the liquid does not create a pressure. The function of the 120 vacuum is to enable the oil or other heating liquid element employed to circulate more freely and it will heat, as is known, more readily under vacuum than under pressure, whereby I am enabled to effect a considerable 125 saving of electrical energy.

130 It will be apparent that by the employment of the clay products or marbles, 31, these marbles, being round, do not entirely fill the hollow columns in the radiator sec-

tions, but leave enough space for the liquid and in heating the liquid, ample space is assured for the circulation.

The function of these clay marbles is, 5 first, to reduce the quantity of oil that it would take to fill the hollow radiator columns, there being present a smaller quantity or liquid to heat, consequently it takes less electrical energy to bring the temperature 10 of the heating element to the predetermined heat, thereby effecting a saving in the cost of operation; second, it takes less electrical energy to keep a small amount of liquid at a predetermined temperature 15 than it does a larger quantity, thus effecting a saving in the cost of operation; third, the clay products or marbles create a latent or storage heat, whereby I obtain without any additional expense, a saving of electrical 20 energy and also acquire an additional amount of heat without any additional cost, when the electrical energy is turned off.

When the electrical energy is turned into the coils, the liquid heats to the pre-determined temperature and the marbles also absorb heat to the same temperature of the liquid, then when the electrical energy is turned off, if it were not for the marbles, this body of liquid would cool quickly.

30 The action on the temperature of the space heated is as follows:—

The circulation of air around the radiator draws off the heat from the cast iron radiator and in doing this naturally cools 35 the temperature of the liquid and due to the fact that we have present an inner column of marbles or clay products, this liquid is supplied with additional heat, which under ordinary conditions does not occur.

40 I have found by actual tests, that when the radiator is filled with oil only, it takes nearly one hour to heat up and 25 minutes to cool down to the temperature of the space heated. When the marbles are also placed in the hollow columns of the radiator, it only takes 23 minutes to bring the radiator to the same temperature and one hour to cool down to the temperature of the room.

50 Special attention is called to the fact that by the provision of the enlarged bottom chamber 5, I am enabled to employ larger tubes 7 to hold the cores 10 and their heating coils 11, thus increasing the 55 heating surface of the coil holders which come in contact with the liquid, because it is well known that the larger the heating surface that comes in contact with any volume of liquid, a greater economy is attained in the heating of said volume of liquid.

From my novel construction of coil holder, it will be evident that any one or more of the coils 11 can be replaced without a total 65 loss of the entire heating unit or element

and one or more of the coils can be readily detached for inspection, replacement or repair, which is a very important feature affecting the practical cost of maintenance.

It will be understood from the foregoing 70 that by my present invention, I have devised an electric radiator adapted to contain a suitable liquid which is subjected to the action of a heating unit comprising a plurality of heating coils and that by using 75 a clay product in conjunction with liquid used a storage of heat or latent heat is obtained.

These coils are so arranged as to be energized and de-energized step by step by individual thermostats controlled by the temperature of the liquid and adjusted to be cut out at different degrees of temperature, so that the radiator can be accurately and automatically controlled within predetermined 80 ranges of temperature and will be automatically controlled in such a manner that any predetermined temperature can be maintained with a minimum consumption of electric current. 90

The upper portion of the left-hand radiator section 17^x is provided with a suitable detachable case 33 provided with a front cover 34 so that on the removal of said case the thermostat 25 is readily accessible 95 and on the removal of the left-hand radiator section 17^x, the air tube 28 is readily accessible.

Upon the removal of the outer cap or bottom plate 22, the head 17 and tubes 7, 100 comprising the heating unit 6 are readily accessible, as is evident, so that all the parts of my novel radiator are convenient of access at all times.

It will be further understood from the foregoing that I have devised an electrical radiator adapted to contain a suitable liquid, which is subjected to the action of a heating unit comprising a plurality of heating coils, which are arranged to be energized 105 and de-energized step by step by individual thermostats controlled by the temperature of the liquid and adjusted to be cut out at different degrees of temperature so that the radiator can be accurately and automatically controlled within predetermined ranges of temperature and will be automatically controlled in such manner that any predetermined temperature can be maintained with a minimum consumption of 110 electrical current. 115

The field of usefulness of this heating system is very large and it can be installed wherever an electric service line is available. In a house containing small apartments, one 125 in each apartment will be sufficient. This system renders it unnecessary to employ heaters in the basement and to employ piping in the basement and through the walls and under the floors of the building. There 130

is nothing to freeze up or leak. It is absolutely noiseless in action. Flues or vents are not needed. The expenses incident to employing a janitor or engineer and the consumption of fuel, wood, oil or gas are dispensed with, as well as the attendant dirt and dust from such operation. It is available for immediate use at any time of the year and at any time of the day or night.

10 It is optional with every occupant of the house in every separate room to have heat or be without it as he desires. Each tenant pays for what he gets and no more. The owner is relieved from any annoyance or expense. These are a few of the advantages in an apartment house, and these advantages apply also to any habitation of man.

15 It can be installed in a tent, a camp, a bunkhouse in the woods, on a ship, in the basement or attic, in the depths of a mine or tunnel, in a palace or a hovel, in a bungalow, a cottage, a farmhouse, a summer camp in the mountains, a garage, a barn, a store or office, and other places too numerous to mention in detail. The radiator is portable and can be plugged in any light socket and it can be manually transported and used by the owner wherever the occasion requires.

20 25 The cost of operation is about twenty five watts per hour to each square foot of radiation, and in this climate the cost to heat an ordinary sized room or small apartment would be about one cent per hour when the k. w. h. rate does not exceed one cent.

30 To state the matter in another way, when the service rate is two cents per k. w. h. it will cost approximately about one twentieth of a cent per hour for a foot of radiation to maintain a temperature of 180°. If the climate is severe, it takes more feet of radia-

tion for the radiator, and the milder the climate, the smaller will be the amount of radiating surface to warm a given space.

45 While I have referred to the liquid heating element as being preferably oil and to the spherical heating elements as being clay marbles, it will be apparent that other equivalent liquid and solid heating elements 50 may be employed without departing from the spirit of my invention.

55 It will now be apparent that I have devised a novel and useful electric radiator which embodies the features of advantage enumerated as desirable in the statement of the invention and the above description, and while I have in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

60 Having thus described my invention what I claim as new and desire to secure by Letters Patent, is—

65 The method of making an electric radiator which consists in assembling the radiator sections, filling them with a liquid heating element and with refractory bodies, electrically heating said liquid and bodies before sealing to a higher degree than would be obtained in actual use, and lastly sealing the radiator when the excess temperature has been reached, thereby creating a vacuum when the heating elements cool.

70 EDMUND B. LENNIG.
